UNITED STATES PATENT OFFICE.

ERIK GUSTAV ERIKSON AND PER L. LINDSTRÖM, OF ARLINGTON, NEW JERSEY.

CENTRIFUGAL CREAM-SEPARATOR.

SPECIFICATION forming part of Letters Patent No. 783,690, dated February 28, 1905.

Application filed December 29, 1903. Serial No. 186,995.

To all whom it may concern:

Be it known that we, ERIK GUSTAV ERIKSON and PER L. LINDSTRÖM, citizens of the United States, residing at Arlington, in the county of Hudson and State of New Jersey, have invented and produced a new and useful Improvement in Centrifugal Cream-Separators; and we do hereby declare the following to be a full, clear, and exact description of the invention, such as will enable others skilled in the art to which it appertains to make and use the same, reference being had to the accompanying drawings, and to numerals of reference marked thereon, which form a part of this specification.

The objects of this invention are to secure increased efficiency in the separation of cream from whole milk; to reduce the cost of constructing the separator and to secure a more simple structure; to facilitate the cleansing of the machine after service; to break up the whole milk into thin film-like streams or currents, whereby the cream-globules are brought into contact with the creaming-surfaces of the liner, and to obtain other advantages and results, some of which may be referred to hereinafter in connection with the description of the working parts.

The invention consists in the improved centrifugal separator and in the arrangements and combinations of parts of the same, all substantially as will be hereinafter set forth and finally embraced in the clauses of the claim.

Referring to the accompanying drawings, in which like numerals of reference indicate corresponding parts in each of the several figures, Figure 1 is a central vertical section of our improved device, taken at line *w*, Fig. 3. Fig. 2 is a section of the same, taken at line *z*. Fig. 3 is a section of the device, taken at line *x*, Fig. 1. Fig. 4 is a detail section taken at line *y*, showing a milk-supply tube and certain lining members or partitions around the same. Fig. 5 is a detail elevation showing certain perforations or slots in the inner members of the improved liner. Fig. 6 is a detail view of the outer member of the liner which may be employed in connection with our invention.

In said drawings, 10 indicates the bowl, 50 which may be seated on a shaft 11 in any suitable manner common in the art. At the central vertical axis of the bowl is arranged a whole-milk tube 12, which extends downward to a longitudinal plate or flange 13 near the 55 bottom of the bowl, the said flange lying a little up from said bottom and held by means of ribs 14 or in any other suitable manner. The said plate or flange 13 is preferably perforated, as shown more clearly at 15 in Fig. 3. 60 Above said flange, within the interior chamber of the bowl, are, arranged hollow perforated liner members or partitions 16 17, which have the form of truncated cones in side elevation. The lower conical partition 16 has 65 its lower larger end seated upon the said flange or plate 13 near its periphery, the said larger end of the conical partition preferably being of a diameter about equal to the diameter of said plate 13 and lying closely near to the interior wall of the chamber within the bowl. The conical partition 16 extends upward from the plate 13 to a point about midway between the opposite ends of the bowl, as indicated in Fig. 1, the smaller upper end being preferably made 70 cylindrical, as shown at 18, to fit telescopedically the smaller lower end 19 of an inverted upper conical member 17. The upper conical partition is thus arranged with its small end downward and its large upper end upward and in 75 engagement with the inner walls of the bowl near the top of said bowl. Where the partition 17 engages the interior walls of the bowl, small lugs or projections 20 are formed, which serve to hold the partition 17 away from said 80 interior walls, so that narrow blue-milk passages 21, Fig. 2, are formed between the said conical partition and the interior walls. We 85 perforate the conical partitions to permit a transmission of fluid from one side to the other. 90 We prefer to form the perforations 23 in said conical partitions as shown in Figs. 1 and 5, the perforations being in the form of slots which are disposed at various angles, so as to 95 form thin eddies or currents within the body of the fluid, so that one current or eddy will be forced into contact with the other as the body of the milk flows upward. Thus this

contact of the eddies tends to cause the cream globules or particles to contact one with another, whereby the said particles will be agglomerated or joined, and thus enlarged to become more perfectly and readily acted upon by centrifugal force. The upper edge of the conical partition is preferably reinforced interiorly by a strengthening-rib 24. While we prefer to employ outside of said partitions 16 5 10 15 20 25 30 35 40 45 50 55 60 65 70 75 80 85 90 95 100 105 110 115 120 125 130

17 another vertical liner, 25, we may dispense with the same and employ the oppositely-flaring partitions alone; but for the purposes of this case we prefer a special form of partition, (shown particularly in Figs. 1 and 6,) the invention of one of the parties to this application. In reassembling the parts we first insert within the bowl the flanged feeding-tube and afterward insert the lower conical partition 16 on its seat on the flange or plate 13. We then apply to the top of the lower said partition the upper partition, the latter being thrust into telescopic relation, as shown in Fig. 1, after which the cover 26 is applied to the bowl in any usual manner. When the outside cylindrical lining-partition 25 is employed, we prefer to insert the same between the large ends of the conical partitions, as shown in Fig. 1. The lower conical partition 16 being first inserted, then the cylindrical partition 25 is placed with its larger end pressing down on the upper edge of the cylinder, the latter being thus held in place. To maintain proper balance, we prefer to provide the bowl with suitable lugs or projections 28, Fig. 3, which enter notches or corresponding recesses in the partitions, by which said parts are held in the proper relation to maintain the desired balance, as will be understood. These recesses and lugs or projections may be arranged in any suitable relation common in the art. The oppositely-disposed conical partitions serve to break up the vertically-movable body of liquid twice in its upward course, the liquid being cut into thin film-like streams or eddies and being forced through the conical partitions twice, once near the bottom of the bowl and again near the top of the bowl, which conduces to a thorough separation of the cream from the blue milk.

In operation the bowl being rotated on its axial shaft 11 in any ordinary manner the new or whole milk is fed down through the tube 12 to the bottom of the bowl, where it spreads out through the passage 29 to the up-passages 15 near the periphery of the bowl, where the milk is brought into almost immediate contact with the inner wall of the lower conical partition 16, on which some of its cream is deposited. In said partition are the variously-inclined long and narrow slots 23, through which the fluid flows, depositing its cream globules or particles on the walls thereof, and this is repeated near the top of the bowl in reverse direction, the very much larger part of the fluid being forced through the upper con-

ical partition and the cream thereof brought into positive contact with the outer surface and walls of the narrow slots, as will be obvious. At the top of the bowl the cream passes out through a cream-exit (not shown) 70 and the blue milk through a blue-milk exit 30 in any usual manner.

Having thus described the invention, what we claim as new is--

1. The improved centrifugal creamer, comprising a bowl arranged on a rotary shaft, a feeding-tube and a liner arranged outside of said tube and comprising two conical partitions separably joined at their small ends and at their larger ends bearing against the wall 80 of the bowl.

2. The improved centrifugal creamer, comprising a bowl arranged on a rotary shaft, a feeding-tube and a liner arranged outside of said tube and comprising two conical and 85 slotted partitions separably joined at their small ends and at their larger ends bearing against the wall of the bowl.

3. The improved centrifugal creamer, comprising a bowl, arranged on a rotary shaft, a feeding-tube and a liner arranged outside of said tube and comprising two perforated conical partitions separably joined at their small ends and at their larger ends bearing against the wall of the bowl.

4. The improved centrifugal creamer, comprising a bowl arranged on a rotary shaft, a feeding-tube, and conical partitions extending around said feeding-tube, the small ends of which telescopically engage one another and the inclined walls of which are perforated at numerous points.

5. The improved centrifugal creamer, comprising a bowl arranged on a rotary shaft, a feeding-tube, and conical partitions extending 105 around said feeding-tube, the small ends of which telescopically engage one another and the inclined walls of which are slotted at numerous points, the slots extending in various directions.

6. The improved centrifugal creamer comprising a bowl arranged on a rotary shaft, a feeding-tube and a liner arranged outside of said tube and comprising two frusto-conical partitions joined at their small ends and at 115 their large ends bearing against the wall of the bowl, substantially as set forth.

7. The improved centrifugal creamer comprising a bowl arranged on a rotary shaft, a feeding-tube and a liner arranged outside of said tube and comprising two frusto-conical partitions joined at their small ends and having perforations at numerous points therethrough, substantially as set forth.

8. The improved centrifugal creamer herein 125 described, comprising a bowl arranged on a rotary shaft, and having a cover with out-passages for cream and blue milk and with a tube extending down therefrom at the axial center of the bowl, the lower end of said tube being 130

open to permit the milk to flow into the main separating-chamber of the bowl, a liner arranged outside of said tube comprising two oppositely-disposed frusto-conical partitions, 5 the large end of one of which lies near the top, and the large end of the other of which lies near the bottom of the bowl, each extending from near the outside of said tube toward the inside wall of the bowl, and each of said 10 frusto-conical partitions being perforated at numerous points throughout its surface to permit an upflow of liquid therethrough, the upflowing liquid first in its course passing through one conical partition and then through 15 the other, and a perforated cylindrical partition disposed in the bowl between, and engaging the outer sides of the large ends of said frusto-conical partitions and being held in place thereby.

20 9. The improved centrifugal creamer, herein described comprising a bowl arranged on a rotary shaft, and having a cover with out-passages for cream and blue milk and with a tube extending down therefrom at the axial center 25 of the bowl, the lower end of said tube being open to permit the milk to flow into the body of the bowl, a liner arranged outside of said tube comprising two frusto-conical partitions joined at their small ends, each extending 30 from near the outside of said tube to the inside wall of the bowl, and each of said frusto-conical partitions being perforated at numerous points throughout its surface to permit an upflow of liquid therethrough, the upflowing liquid first in its course passing through 35 one conical partition and then through the other, and a perforated cylindrical partition arranged between the conical partitions.

10. The improved centrifugal creamer here-

in described, comprising a bowl arranged on 40 a rotary shaft and having a cover thereon with out-passages for the separated fluids and having a milk-tube extending down into said bowl at the axial center of said bowl, the lower end of said tube being open to permit an outflow 45 of the milk, and a plurality of frusto-conical partitions lying one above the other in the space between the tube and inner wall of the bowl, said conical partitions being perforated at numerous points, the perforations being 50 distributed over the surface of the partitions, and a cylindrical lining-partition interposed between the large end of the conical partitions.

11. The improved centrifugal creamer herein described, comprising a bowl arranged on 55 a rotary shaft and having a cover thereon with out-passages for the separated fluids and having a milk-tube extending down into said bowl at the axial center of said bowl, the lower end of said tube being open to permit an outflow 60 of the milk, and a plurality of frusto-conical partitions lying one above the other in the space between the tube and inner wall of the bowl, said conical partitions being perforated at numerous points, the perforations being 65 distributed over the surfaces of the partitions, the small upper end of the lower partition being in connection with and held by the lower end of the upper conical partition.

In testimony that we claim the foregoing 70 we have hereunto set our hands this 10th day of December, 1903.
